UNITED STATES PATENT OFFICE

LOUIS C. STUKENBORG, OF MEMPHIS, TENNESSEE

HYDRAULIC ELEVATOR

Application filed November 12, 1930. Serial No. 495,069.

This invention relates to improvement in hydraulic elevators and has especial relation to a device of this kind in which the elevator is raised by pumping liquid into the elevator cylinder. It further relates particularly to a device of this kind in which the pump is more or less remote from the elevator and in which the actuation of the pump is governed by remote control. It further relates to a device of this kind in which the raising fluid is in a closed circuit and particularly to a device in which the pump and the motor therefor are enclosed in the fluid reservoir and a release valve interlocked with the motor control is also carried by the fluid reservoir.

The objects of the present device are:

(a) To provide a pump and motor and an enclosing casing therefor which will also serve as a fluid reservoir whereby a unitary device is accomplished and the noise inherent in the operation of a high speed pump and motor of this kind is minimized and absorbed;

(b) To provide a normally full return flow line whereby initial discharge inertia will be set up, and surge or drops due to air pockets in the line will be eliminated;

(c) To provide electrically operated control means for a hydraulically actuated elevator mechanism; and

(d) To provide an interlocked remote control for the actuation of such a device.

The means by which the foregoing and other objects are accomplished, and the manner of their accomplishment will readily be understood from the following specification on reference to the accompanying drawings, in which:

Fig. 1 is a sectional elevation taken on the vertical center line of the fluid reservoir and through the elevator pit and disclosing diagrammatically the remote control for the device.

Fig. 2 is an enlarged diagrammatic view showing a typical form of control.

Fig. 3 is a sectional elevation of the reservoir and associated mechanism; and

Fig. 4 is a sectional plan taken on the line IV-IV of Fig. 3; these latter views being substantially twice the scale of Fig. 1, and

showing a modification of the arrangement of the parts.

Referring now to the drawings in which the various parts are indicated by numerals, 10 is an elevator pit in which the upper end 55 11 of a hydraulic elevator cylinder is disposed. This cylinder extends downward below the bottom of the pit to such depth as may be necessary for the particular elevator involved. 12 is a plunger disposed in this 60 cylinder and 13 a superstructure secured thereto. 14 is the floor of an elevator which floor is supported by the super-structure 13. 15 indicates the side walls of the elevator cage. 16 are posts or guides for the elevator 65 which may be used should it be so desired.

17 is a tank or reservoir for the liquid, ordinarily oil, which is used in raising the plunger of the elevator. Mounted within the tank is an electric motor 18, which is directly 70 connected to a pump 19 from which a discharge pipe 20 leads to the cylinder 11. 21 is a strainer covered inlet to the pump 19. 22 is a check valve in the discharge pipe 20, preventing return flow therethrough to the 75 pump. 23 is a by-pass line leading from the line 20 between the check valve 22 and the cylinder back into the tank 17. 24 is a normally closed release valve disposed in the by-pass line and 25 a solenoid for opening and 80 closing this valve. 26 is a shock absorber for absorbing "water-hammer" in the pipe line 23.

In Figs. 3 and 4 the valve 24 is positioned about level with the bottom of the reservoir 85 17, and the tail pipe 23A, leading therefrom is carried into the reservoir so that it will rest on the bottom thereof, so that at all times such pipe will be full. Preferably also this pipe is continued within the reservoir in a 90 coil 23B so that additional inertia will be set up in such by-pass line. In this modification, the pump inlet is preferably carried definitely above the level of the tail pipe 23A.

27 is a motor starter, 28 a solenoid starter and 29 are push button panels, two of which are shown in Fig. 1, and three in Fig. 2. Each of these panels has three control buttons. The first of these buttons 30, is used 95 to start the motor 18 and raise the elevator. 100

The second button 31 is used to stop the elevator, either going up or down, and the third button 32 to lower the elevator. These buttons ordinarily carry designations such as 5 Up, Stop, and Down, respectively, to indicate their use for such purposes. These buttons are connected by suitable wiring with the motor starter and solenoid starter. Where a control is carried on the elevator the 10 connection is by flexible insulated wires, which ordinarily are collected into a flexible cable 33.

In Fig. 2, I have shown diagrammatically a typical layout by which this control may 15 be accomplished. Referring now to that drawing a pair of wires 34 leads from the button 30 to switch actuating means, shown as a magnet 35, which magnet when energized by this circuit closes the switch 36 and starts 20 the motor 18, these circuit wires also lead through a second magnet 37 in the solenoid box 38, which magnet 37 when energized opens the switch 39 which actuates the solenoid 25 so that when the button 30 is pushed 25 to start the motor the solenoid controlled valve is also closed.

A second pair of wires 40 leads from the stop button 31 to the magnet 37 which accomplishes opening of the solenoid switch 30 and to a magnet 41 which when energized opens the motor switch 36 thereby cutting off the motor, so that pushing the stop button at one and the same time, shuts off the motor and closes the solenoid switch.

35 A third pair of wires 42 leads from the down button 32 to a third magnet 43 which when energized closes the switch 39 and energizes the solenoid 25 to open the solenoid control valve 24. These circuit wires also 40 lead to the magnet 41 which opens the motor switch 36 whereby the motor circuit is broken at the same time that the solenoid circuit is actuated.

It will be noted that the buttons on the 45 panels may be used interchangeably so that a cycle of control may be accomplished from one panel or from two or even more panels as may be desired.

It will be understood that the various units 50 herein shown may be largely purchased in the open market so that the detail thereof need not here be shown.

It will be seen that I have combined into a 55 self-contained unit the tank which serves as a reservoir for the lifting unit, the pump which transfers this liquid to the cylinder, the check valve which prevents return flow through the pump discharge pipe, the bypass line and the release valve therefor, 60 which permits accomplishment of the return flow through the tank, and by the use of remote controls have accomplished the utilization of such a unit and its control from such remote points.

65 It will further be noted that the pump and

motor in the present case are preferably of high speed type, which types are inherently more or less noisy and that by mounting and enclosing the motor within the tank and the pump in direct contact and partially submerged in the liquid within the tank, that such liquid serves to deaden and greatly reduce if not to eliminate the noise incident to such operation.

It will be further noted as disclosed in 75 Figs. 3 and 4, that in bringing the tail line 23A, leading from the control valve 24 into the bottom of the reservoir, and extending it to some length that I am able to maintain a considerable amount of oil in this line adjacent the control valve and that by keeping this line full of oil, inertia and back pressure due to friction in the pipe minimize the sudden drop which occurs, and which however small, is incident to the ordinary operation of hydraulic elevators, and that keeping the pipe full of oil also prevents the formation of air pockets therein, which pockets cause slight but nevertheless unpleasant jars when the control valve is first opened.

Having described my invention, what I claim is:

1. A hydraulic elevator operating unit comprising a reservoir for the liquid, a pump and a motor associated therewith, a hydraulic connection from said pump to the cylinder of said elevator, valve controlled means for allowing return flow from said hydraulic connection to said reservoir, said means comprising a pipe of substantial length having 95 its discharge end terminating in a horizontal coil, said coil having a plurality of turns of decreasing radii and being disposed within the reservoir, and said pump having its intake opening above the level of said coil, whereby submergence thereof is maintained.

2. A hydraulic elevator operating unit comprising a reservoir for the liquid, a pump and a motor associated therewith, a hydraulic connection from said pump to the cylinder of said elevator, a check valve in said connection preventing return flow through said pump, valve controlled means for allowing return flow from said elevator to said reservoir, said means comprising a pipe of substantial length having a discharge end terminating in a horizontal coil, said coil having a plurality of turns of decreasing radii and being disposed within the reservoir, and said pump having its intake opening above 110 the level of said coil, whereby submergence thereof is maintained.

In testimony whereof I hereunto affix my signature.

LOUIS C. STUKENBORG.
